(57) **CLAIM**

The ornamental design for a side wall combination for a beam, as shown and described.

DESCRIPTION

FIG. 1 is a perspective view of a side wall combination for a beam in accordance with the present design;

FIG. 2 is a front view thereof;

FIG. 3 is a back view thereof;

FIG. 4 is a top view thereof;

FIG. 5 is a bottom view thereof; and,

FIG. 6 is a first end view thereof. The second end view is substantially identical to the first end view.
